UNITED STATES PATENT OFFICE.

MORRIS SCHWARTZ, OF BROOKLYN, NEW YORK.

VEST-HOLDER.

987,262.

Specification of Letters Patent. Patented Mar. 21, 1911.

Application filed June 10, 1910. Serial No. 566,260.

To all whom it may concern:

Be it known that I, MORRIS SCHWARTZ, a subject of the Czar of Russia, residing at Brooklyn, Kings county, in the State of New York, have invented certain new and useful Improvements in Vest-Holders, of which the following is a clear, full, and exact description.

This invention relates to vest-holders, and has for its object to provide a device one end of which may be applied to a vest, and the other end of which may be applied to an adjacent garment, preferably the trousers, for the purpose of holding the vest down to avoid wrinkling thereof. When in position upon the garments above named the holding device will be concealed.

I will now proceed to described my invention in detail, the novel features of which will be pointed out in the appended claim, reference being had to the accompanying drawing, forming part hereof, wherein:—

Figure 1 is a diagrammatic view showing a portion of a vest and trousers, my improved vest-holder being shown in position, in dotted lines; Fig. 2 is an enlarged face view of my improved vest-holder; Fig. 3 is an edge view thereof, looking from the right in Fig. 2; and Fig. 4 is an enlarged vertical sectional view taken on a line $a-a$ in Fig. 1.

Referring to Fig. 1, the meeting ends of a vest are indicated by 1 and 1^a, and the meeting members of a trousers by 2 and 2^a. The vest member 1^a is provided with buttons 3, as is usual and the member 1 with button-holes 4. The trousers-members are also provided with buttons 5 and button-holes 6.

As can be seen in Figs. 2 and 3 my improved vest-holder consists of an upper engaging member 7 and a lower engaging member 8, each of said members being provided with slots 9, which are adapted for the passage of the shank of a vest-button, such as is indicated by 3, or for the group of threads which forms a connecting element for the material of the vest, or trousers, and the button, in the event of the vest or trousers being provided with buttons that are sewed on. The button 3 herein indicated

and illustrated in Fig. 3 is a well known form of metal, pearl or celluloid button which is sewed to the vest. The slot 9 is preferably of the contour shown in Fig. 2, *i.e.* having a mouth portion 9^a, the straight portion 9^b and curved or angular portion 9^c.

To relieve the vest button from the entire strain exerted upon the upper member 7 of the holder, by the movement of the body, I provide the said upper member 7 with an auxiliary catch 11 pivoted at 11^a, the upper end of the catch being turned over to form a hook 12, the said hook being adapted to pass through the hole for the button with which the said upper member 7 may be engaged (see Fig. 4), and to engage the fabric of the vest adjacent the button-hole. In case the threads securing the button to which the member 7 is applied should become worn or break, the auxiliary catch 11 will hold the device in operative position, as the hook 12, engaging the edge of the button-hole will support the member 7.

As can be seen in Figs. 2 and 3, the members 7 and 8 are connected by a strap 10, which is preferably elastic.

To apply my improved vest-holder, it is but necessary to pass the upper catch member 7 over the shank of the vest button, and between the meeting ends thereof as shown in Fig. 3. The pivotal auxiliary catch 11 can then be caused to engage the material of the vest, see Fig. 3. After having secured the upper catch 7, the lower catch 8 can be caused to engage a trousers button (see Fig. 1).

The length of the slot 9 in the members 8 and 7 precludes any chance of the said members slipping off their engaged buttons when the elastic band 10 is relaxed. The band 10 will give and relax with the movement of the body.

Having now described my invention what I claim and desire to secure by Letters Patent is:—

A button engaging plate provided with means for attachment to a tape and with a slot adapted to receive the shank of a button, the entrance of the slot being located

intermediate the ends of the plate and at the side thereof, and an auxiliary catch, one end of the catch being pivoted to said plate, the opposite end thereof having a hook, adapted to take into a button hole and engage the fabric adjacent thereto when the slot in the plate engages the button shank, said catch adapted when in engaged posi-

tion to form a lock to prevent the escape of the button shank from the slot.

Signed at New York city, N. Y., this 9th day of June 1910.

MORRIS SCHWARTZ.
